COMBINED PACKAGING AND DISPENSING TRAY FOR RAZOR BLADE UNITS

Edward E. Pomfret, Newbury, England, assignor to
The Gillette Company, Boston, Mass.

Filed July 17, 1972, Ser. No. 272,204

Claims priority, application Great Britain Feb. 2, 1972

Term of patent 14 years

Int. Cl. D9—03

U.S. Cl. D9—189

FIG 1

FIG 2

FIG 3

FIG 4

FIG 5

FIG 6

FIG 7

FIG. 1 is a plan view of a combined packaging and dispensing tray for razor blade units showing my new design;

FIG. 2 is a side elevational view of the lower side of the tray as viewed in FIG. 1;

FIG. 3 is a side elevational view of the upper side of the tray as viewed in FIG. 1;

FIG. 4 is an end elevational view from the left end of the tray as viewed in FIG. 1;

FIG. 5 is a sectional view taken along the line 5—5 of FIG. 1;

FIG. 6 is a sectional view taken along the line 6—6 of FIG. 1; and

FIG. 7 is a sectional view taken along the line 7—7 of FIG. 1.

I claim:

The ornamental design for a combined packaging and dispensing tray for razor blade units, as shown.
